ROCK DRILLING MECHANISM

Original Filed Oct. 12, 1923

UNITED STATES PATENT OFFICE

THORE R. E. RUNDQVIST, OF CLAREMONT, NEW HAMPSHIRE, ASSIGNOR TO SULLIVAN MACHINERY COMPANY, A CORPORATION OF MASSACHUSETTS

ROCK-DRILLING MECHANISM

Application filed October 12, 1923, Serial No. 668,197. Renewed October 10, 1929.

My invention relates to rock drilling mechanisms.

An object of my invention is to provide an improved rock drilling mechanism. Another object of my invention is to provide an improved feeding mechanism for a rock drilling mechanism of the pressure fluid operated percussive type. A further object of my invention is to provide an improved controlling mechanism for the pneumatic feeding mechanism of a rock drill of the pressure fluid operated percussive type, and more particularly one adapted to control the pressure in the feeding means during spotting of the hole. A still further object of my invention is to provide an improved controlling mechanism which is automatically controlled by the variations in pressure within the feeding means and more particularly adapted to prevent accidental collapse of the feed. These and other objects and advantages of my invention will hereinafter more fully appear.

In the accompanying drawings I have shown for purposes of illustration one form that my invention may assume in practice.

In these drawings,—

Fig. 1 is a front elevation, partially broken away, of a drilling mechanism in which my improved feed controlling mechanism is incorporated.

Fig. 2 is a central longitudinal sectional view taken substantially on line 2—2 of Fig. 1.

Fig. 3 is a transverse sectional view taken substantially on line 3—3 of Fig. 2.

Fig. 4 is a detail view of a part of my improved controlling mechanism.

Fig. 5 is a detail sectional view, taken substantially on line 5—5 of Fig. 1, through the throttle valve, showing the motor and feed supply ports.

In this illustrative form of my invention I have shown a drilling mechanism of the so-called "stoper" type generally designated 1, which comprises a drilling motor 2 of the pressure fluid percussive type which is adapted to percussively actuate a drill steel 3 carried in the front end of the drilling mechanism, and a feeding mechanism

generally designated 4 of the pressure fluid operated type. This feeding mechanism comprises a feed cylinder 5 and a piston 6 reciprocable therein having a piston rod 7 provided with a point 8 adapted to engage an extraneous abutment during the drilling operation. The drilling motor parts and the feeding mechanism are suitably held together by means of side rods including bolt heads or nuts 9, in a well known manner. Suitably secured in a head member 10 of the drilling motor is a laterally projecting handle 11 having a grasping portion 12 which is used for supporting the drilling mechanism during the drilling operation and to rotate the drill steel 3 if automatic rotation is not present.

Suitably secured in a boss 13 formed integral with the head block 10 is a valve bushing 14, which has a conical bore 15 formed therein in which a throttle valve 16 is disposed. Herein, the throttle valve has a hollowed out portion 17 to which pressure fluid is admitted through a swiveled pipe connection 18 from any suitable source of supply. The throttle valve 16 is traversed by a port 19 which is adapted to be connected to a passage 20 (see Fig. 2) leading to the distribution ports of the drilling motor in a well known manner. A bore 21 is formed coaxially in the valve 16 and communicates at its forward end by a port 22 with the chamber 17. Opening laterally from the bore 21 is a port 23 communicating with a groove 24 extending longitudinally of the valve in the periphery thereof. Herein the groove 24 communicates with a circumferentially extending groove 25 which in turn communicates with a port 26 leading to the interior of the feed cylinder. An auxiliary control valve 27 having a generally conical end 28 is longitudinally reciprocable in the bore 21 and is provided with a head or collar 29 against which a spring 30 presses to maintain the valve in wide open position, thereby permitting communication between the ports 22 and 23. A small passage 31 extends longitudinally of the valve 27 which is adapted to communicate by way of a port 32 with the port 23.

leading to the feed cylinder and to the atmosphere. An operating lever 33 is pivoted at 34 in a main throttle valve operating handle 35 and is adapted when pressed by the operator to cause the closing of the valve 27 bringing the port 32 in communication with the port 23, consequently cutting off the air supply through the port 26 communicating with the feed cylinder and venting the feed cylinder to the atmosphere through the passage 31. Circumferentially spaced from the port 19 in the throttle valve 16 is a port 36 which is adapted to communicate with a port 37 leading to my improved automatic feed controlling mechanism to be now described.

Herein it will be noted that the piston rod 7 is provided with a hollow bore 38 throughout its length in which a sleeve member 39 is reciprocable. The sleeve 39 is provided with a plurality of oppositely disposed slots or grooves 40 and 41, in which grooves 40 a plurality of friction springs 42 are disposed. These springs are adapted to frictionally engage the walls of the bore 38 tending to hold the sleeve stationary. Longitudinally reciprocable in a bore 43 formed in the sleeve 39 is a cylindrical slide valve 44 which is suitably secured to an inner head member 10', suitably secured to the head block 10 by means of a hollow rod 45, which is in turn threaded as at 46 and 47, respectively, to the valve and the head member 10'. The valve is provided with a longitudinally extending bore 48 and is perforated by a series of ports 49 which are adapted to communicate with a series of ports 50 formed in the sleeve 39. Pressure fluid is adapted to be admitted to the bore 48 by means of the passage 37 leading from the valve 16. The opposite ends of the valve 44 are provided with stop members 51 and 52 with which the sleeve 39 is adapted to engage under certain conditions.

In the operation of my improved mechanism, the point 8 of the feed piston rod 7 is placed against an abutment a suitable distance from the working face, the drilling mechanism being supported by the handle 11 at this time. The operator then manipulates the valve 16 to the position shown in Fig. 2 and Fig. 5, bringing the grooves 24 and 25 which communicate with the pressure fluid supply chamber 17 into communication with the ports 26 and 37 admitting fluid pressure to the feed cylinder from the chamber 17 through ports 22 and 23, grooves 24 and 25 and port 26 under control of the valve 27 and causing the feed cylinder to move upwardly relative to the feed piston, consequently bringing the drill steel adjacent the work, the ports 49 and 50 being closed at this time as shown in Fig. 2. The feed control valve 27 is then closed by swinging the lever 33 to the left

in Fig. 1, thereby cutting off the air supply to the feed cylinder through the port 26 and opening the port 31 venting the feed cylinder to atmosphere, consequently stopping the feed. As a result of this reduction of pressure in the feed cylinder the drilling motor, the feed cylinder, the rod 45, and the valve 44 will fall downwardly relative to the feed piston rod, the stop 51 engaging the sleeve 39 and thereby opening the communication between the ports 49 and 50. This will cause a greater amount of pressure air to flow from the hollow rod 45 into the feed cylinder than is being vented out through the vent 31, so the drill will again move up to the work. Communication between the ports 49 and 50 again is cut off by the sleeve 39 which frictionally engages the bore of the stationary piston rod. The pressure again drops in the feed cylinder, the vent passage 31 still remaining open, again causing the drilling motor and feed cylinder to drop back relative to the feed piston, again opening communication between the ports 49 and 50, simultaneously again moving the ports 49 out of communication with the ports 50, the sleeve 39 tending to remain stationary, by means of the springs 42 engaging the walls of the bore 38, until the stop 52 engages the valve, the sleeve and valve thereafter moving simultaneously until the drill again falls back. This operation is repeated as long as the vent passage 31 remains open substantially balancing the feed within the limits of the stop members 51 and 52 with the drill steel 3 positioned at the desired distance from the working face. The valve 16 is then further rotated bringing the port 19 in communication with the passage 20, thereby starting the drilling motor and "spotting" the hole. After the hole is spotted the lever 33 is released causing the passage 31 to be closed, the drill again moving forwardly by means of pressure fluid passing through the port 26. The ports 49 and 50 are closed during the forward feed of the drilling motor as shown in Fig. 2. It will also be noted if a soft spot or seam is encountered during the drilling operation, the jumping of the drill is prevented by quickly closing the valve 27 consequently cutting off the flow of fluid through passage 26. It is also obvious that the falling of the drilling mechanism in this case is also prevented by the automatic control valve 44. It will herein also be noted that when the supply of fluid to the feed cylinder 5 and the vent port 31 is closed with only the supply of fluid to the conduit 45 open the pressure fluid is trapped in the feed cylinder and as this pressure gradually reduces, due to inherent leakage between the feeding parts, the feed cylinder moves rearwardly relative to the stationary feed pis-

ton. Such rearward movement causes the ports 49 in the slide valve 44 to move into communication with the ports 50 in the sleeve 39, thus admitting a supplemental supply of pressure fluid from the conduit 45 to the feed cylinder, thereby automatically maintaining the pressure therein above a predetermined minimum and preventing the dropping of the drill steel away from the work.

As a result of my improvement it will be obvious that the feed during "spotting" may be readily controlled and that the accidental falling of the drill caused by the drop in pressure above the piston in the feed cylinder is entirely eliminated, thereby preventing the flying of the drill steel and the falling of the drilling mechanism which frequently injures the operator and damages the drill. It will also be noted that falling of the drill, caused by the operator unwittingly closing off the feed while maintaining the motor running, is prevented. It will also further be noted that the controlling mechanism is of simple structure and that it may be applied to a drill of standard form with a minimum of change.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rock drilling mechanism, the combination with a drilling motor, and fluid actuated feeding means therefor comprising cooperating feeding members adapted to have relative movement, of feed controlling means for controlling said relative movement comprising a controlling element movable with one of said feeding members and a cooperating controlling element engageable with the other feeding member, said controlling elements being movable relative to each other upon relative movement of said feeding members in one direction for controlling fluid flow to said feeding means.

2. In a rock drilling mechanism, the combination with a drilling motor, and fluid actuated feeding means therefor comprising cooperating feeding members adapted to have relative movement, of fluid controlling means for said feeding means for effecting relative movement between said members comprising cooperating relatively movable controlling elements engageable respectively with said feeding members, one of said controlling elements slidably engaging one of said feeding members.

3. In a rock drill, the combination with

a drilling motor, and fluid actuated feeding mechanism therefor comprising a stationary member and a movable member, of means for controlling the flow of fluid to said feeding mechanism including an element carried by said movable feeding member and a co-operating element slidably engageable with said stationary feeding member.

4. In a rock drill, the combination with a drilling motor, fluid actuated feeding mechanism therefor comprising a source of pressure fluid, cooperating feed cylinder and piston members adapted to have relative movement, and means for controlling the connection of said source with said cylinder, of supplemental fluid controlling means for said feeding mechanism including a controlling element carried by one of said feeding members, and a cooperating controlling element engageable with the other feeding member, said controlling elements being relatively movable upon relative movement of said feeding members in one direction for controlling fluid flow to said feeding means.

5. In a rock drill, the combination with a drilling motor, and fluid actuated feeding mechanism therefor comprising cooperating feed cylinder and piston members adapted to have relative movement, of means for controlling the pressure in said feed cylinder including a valve element carried with the latter and a cooperating valve element engageable with said piston, one of said valve elements being movable relative to the other to control fluid flow to said feeding mechanism.

6. In a rock drill, the combination with a drilling motor, and fluid actuated feeding mechanism therefor comprising a plurality of cooperating feeding members adapted to have relative movement, of means for controlling the flow of fluid to said feeding mechanism including a valve element carried with one of said feeding members and a cooperating valve element frictionally engageable with the other feeding member.

7. In a rock drill, the combination with a drilling motor, and fluid actuated feeding mechanism therefor comprising cooperating relatively movable cylinder and piston members, of means for controlling the pressure to said feed cylinder including a controlling element carried with one of said feeding members, and a cooperating controlling element frictionally engageable with the other feeding member.

8. In a drilling mechanism, the combination with a drilling motor, feeding means therefor including relatively movable feeding elements, means for supplying pressure fluid to said feeding means for actuating the latter including separate passages, manual means for controlling one of said passages, of means operative upon relative movement between said feeding elements

for automatically controlling another passage when said first passage is closed by said manual means, said automatic means being operative when the pressure in said feeding means drops below a predetermined minimum and including controlling elements respectively engaging said feeding elements.

9. In a drilling mechanism, the combination with a drilling motor, and feeding means therefor including a cylinder and cooperating piston, of means for automatically controlling the pressure fluid supply to said feeding means including cooperating elements one movable with said drilling motor and another frictionally engageable with one of said feeding elements.

10. In a drilling mechanism, the combination with a drilling motor, pressure fluid actuated feeding means therefor including relatively movable elements, and a source of pressure fluid, of mechanically actuated means dependent upon movement between said feeding elements in one direction for opening automatically communication between said source and said feeding means thereby maintaining the pressure in the latter above a predetermined minimum, said means being automatically operative to supply fluid to said feeding means when the pressure therein drops below said minimum pressure.

11. In a drilling mechanism, the combination with a drilling motor, pressure fluid actuated feeding means therefor including relatively movable feeding elements, and means for normally controlling the supply of fluid thereto, of mechanically actuated means dependent upon relative movement between said feeding elements to maintain automatically a predetermined pressure in said feeding means when said first mentioned fluid supply is closed by said controlling means.

12. In a drilling mechanism, the combination with a drilling motor, pressure fluid actuated feeding means therefor including a stationary member and a movable member, and a source of pressure fluid, of means including cooperating fluid controlling elements engageable respectively with said members and dependent upon relative movement between said feeding members to open automatically communication between said source and said feeding means when the pressure in said feeding means drops below a predetermined minimum.

13. In a drilling mechanism, the combination with a drilling motor, a drill steel actuated thereby, pressure fluid actuated feeding means therefor including relatively movable feeding elements, and means normally controlling the flow of fluid thereto, of mechanically actuated, supplemental fluid controlling means dependent upon relative

movement between said feeding elements to maintain automatically the drill steel in substantially operative position adjacent the work when the normal flow of fluid to said feeding means is closed by said controlling means.

14. In a drilling mechanism, the combination with a drilling motor, a drill steel actuated thereby, pressure fluid actuated feeding means therefor including a stationary member and a movable member, and means for normally controlling the flow of fluid thereto, of means including cooperating fluid controlling elements engageable respectively with said feeding members and automatically operative to maintain the drill steel in substantially operative position adjacent the work when the normal flow of fluid to said feeding means is closed by said first mentioned controlling means.

15. In a drilling mechanism, the combination with a drilling motor, pressure fluid actuated feeding means therefor including a stationary member and a movable member, and controlling means for opening and closing a supply of fluid to said feeding means, of means including cooperating fluid controlling elements engageable respectively with said members and automatically operative upon relative movement between said feeding members to maintain a predetermined pressure in said feeding means when said fluid controlling means is closed.

16. In a drilling mechanism, the combination with a drilling motor, a drill steel actuated thereby, pressure fluid actuated feeding means for said steel including a movable feed cylinder and a cooperating stationary feed piston, means for normally supplying pressure fluid to said feeding means, and controlling means for opening and closing said normal fluid supply, of means including cooperating fluid controlling elements engageable respectively with said cylinder and piston and operative upon relative movement between said cylinder and piston for automatically maintaining the pressure in said feeding means up to a degree sufficient to maintain the drill steel adjacent the work when said normal fluid supply is closed by said first mentioned controlling means.

17. In a drilling mechanism, the combination with a drilling motor, a drill steel actuated thereby, pressure fluid actuated feeding means therefor including relatively movable feeding elements, and manually operable means for normally controlling the flow of fluid thereto, of mechanically actuated means positively actuated upon relative movement between said feeding elements and automatically operative to substantially balance by pressure fluid the drill steel in position adjacent the work when the normal fluid supply to said feeding means is closed

by said manually operable controlling means.

18. In a drilling mechanism, the combination with a drilling motor, a drill steel actuated thereby, pressure fluid actuated feeding means therefor including relatively movable feeding elements, and manually operable venting means for reducing the pressure in said feeding means, of means automatically operative when the pressure in said feeding means is reduced and positively actuated upon relative movement between said feeding elements for preventing reverse feeding movement of said feeding means and the consequent dropping of the steel away from the work.

19. In a drilling mechanism, the combination with a drilling motor, a drill steel actuated thereby, and pressure fluid actuated feeding means therefor including a stationary member and a movable member, of means dependent upon relative movement between said members and including cooperating fluid controlling elements engageable respectively with said members for substantially balancing said feeding means with the drill steel in operative position adjacent the work.

20. In a drilling mechanism, the combination with a drilling motor, pressure fluid actuated feeding means therefor including relatively movable feeding elements, and means for controlling the pressure in said feeding means including vent means for reducing the feeding pressure, of means dependent upon relative movement between said feeding elements caused by the reduction in feeding pressure for substantially balancing automatically said feeding means when said vent means is opened.

21. In a rock drill, the combination with a drilling motor fluid actuated feeding mechanism therefor comprising relatively movable feeding elements, a main supply of pressure fluid therefor, and means for normally controlling said main fluid supply, of a supplemental supply of pressure fluid for said feeding mechanism, and mechanically actuated means dependent upon relative movement between said feeding elements for opening automatically said supplemental supply when said main supply is closed by said controlling means, said automatic means being operative when the pressure in said feeding means drops below a predetermined minimum.

22. In a drilling mechanism, the combination with a drilling motor, fluid actuated feeding means therefor comprising relatively movable feeding elements, and manually operable means for controlling the supply of fluid thereto, of means positively actuated upon relative movement between said feeding elements to reciprocate automatically said feeding means between pre-

determined limits when said manually controlled supply is closed by said manually operable means.

23. In a drilling mechanism, the combination with a drilling motor, pressure fluid actuated feeding means therefor comprising relatively movable feeding elements, and controlling means for supplying fluid to said feeding means to effect relative movement between said feeding elements in one direction, of means automatically operative to admit a separate supply of pressure fluid to said feeding means when movement between said feeding elements occurs in an opposite direction, said automatic means including controlling elements respectively engageable with said feeding elements.

24. In a drilling mechanism, the combination with a drilling motor, pressure actuated feeding means therefor including relatively reciprocable cylinder and piston elements, fluid supply means for said feeding means, and manually operable means for controlling said supply to admit pressure fluid to said feeding means to effect feeding movement in one direction, of a supplemental fluid supply for said feeding means, and means including controlling elements respectively connected to said feeding elements and automatically operative upon relative movement between said feeding elements in the opposite direction for automatically opening said supplemental fluid supply.

25. In a rock drill, in combination, a drilling motor for actuating a drill steel, pressure fluid actuated feeding means for said motor including relatively reciprocable feeding elements, and means for effecting controlled supply of feeding pressure fluid to said feeding means including means for controlling the flow of pressure fluid to said feeding means to effect feed in one direction, and automatic feed controlling means dependent upon relative movement between said feeding elements in the reverse direction for controlling flow of pressure fluid to said feeding means.

26. In a rock drill, the combination with a drilling motor for actuating a drill steel, pressure fluid actuated feeding means for said motor including relatively reciprocable feeding elements, and means for controlling the flow of pressure fluid to said feeding means to effect feed in one direction, of a supplemental fluid supply for said feeding means, and automatic fluid controlling means dependent upon relative movement between said feeding elements in the reverse direction for controlling the flow of pressure fluid from said supplemental supply to said feeding means.

27. In a rock drill, in combination, a drilling motor for actuating a drill steel, pressure fluid actuated feeding means for said motor including relatively reciprocable

feeding elements, and means for effecting controlled supply of feeding pressure fluid to said feeding means including means for controlling the flow of pressure fluid to said feeding means to effect feed in one direction, and automatic feed controlling means dependent upon relative movement between said feeding elements in the reverse direction for controlling flow of pressure fluid to said feeding means, said automatic controlling means including relatively movable fluid controlling elements one of which is movable with one of said feeding elements and the other of which is operatively connected to the other feeding elements.

28. In a rock drill, in combination, a drilling motor for actuating a drill steel, pressure fluid actuated feeding means for said motor including relatively reciprocable feeding elements, means for effecting controlled supply of feeding pressure fluid to said feeding means including means for controlling the flow of pressure fluid to said feeding means to effect feed in one direction, and automatic feed controlling means dependent upon relative movement between said feeding elements in the reverse direction for controlling flow of pressure fluid to said feeding means, said automatic controlling means including relatively movable fluid controlling elements one of which is movable with one of said feeding elements and the other of which is operatively connected to the other feeding elements, and a lost motion connection between said latter controlling element and one of said feeding elements.

29. In a rock drill, the combination with a drilling motor for actuating a drill steel, pressure fluid actuated feeding means for said motor including relatively movable feeding elements, a passage for normally supplying pressure fluid to said feeding means, and controlling means for said passage, of automatic controlling means for said feeding means operative when the pressure in said feeding means drops below a predetermined minimum and including a separate passage for conducting a supplemental supply of pressure fluid to said feeding means when said normal supply is closed, and means operative to control said last mentioned passage to control relative movement between said feeding elements including a control member having opposed surfaces of equal area subjected to the pressure in said feeding means.

30. In a rock drill, the combination with a drilling motor for actuating a drill steel, pressure fluid actuated feeding means for said motor including relatively movable feeding elements, a passage for normally supplying pressure fluid to said feeding means, and controlling means for said passage, of automatic controlling means for

said feeding means operative when the pressure in said feeding means drops below a predetermined minimum and including a separate passage for conducting a supplemental supply of pressure fluid to said feeding means when said normal supply is closed, means operative to control said last mentioned passage to control relative movement between said feeding elements including a control member having opposed surfaces of equal area subjected to the pressure in said feeding means, and means operative when the pressure in said feeding means drops below a predetermined minimum for subjecting said control member to an actuating force previously non-existent to move said member in one direction to open said supplemental fluid supply.

31. In a rock drill, the combination with a drilling motor for actuating a drill steel, and pressure fluid actuated feeding means for said motor including relatively reciprocable cylinder and piston elements, of means for effecting controlled supply of feeding pressure fluid to said feeding means including automatic controlling means for controlling the feeding pressure in said feeding means including a controlling element having equal opposed pressure areas constantly subjected to the pressure in said feeding means, whereby said controlling element is maintained in a substantially balanced condition, and means responsive to pressure conditions in said feeding means for subjecting said controlling element to a superior pressure to unbalance said controlling element to move the same in one direction.

In testimony whereof I affix my signature.
